CLAIM

The ornamental design for a safety switching device, as shown and described.

DESCRIPTION

FIG. 1 is a perspective view of a first embodiment of the safety switching device embodying our new design;

FIG. 2 is a front view of the safety switching device shown in FIG. 1;

FIG. 3 is a rear view of the safety switching device shown in FIG. 1;

FIG. 4 is a top view of the safety switching device shown in FIG. 1;

FIG. 5 is a bottom view of the safety switching device shown in FIG. 1;

FIG. 6 is a left side view of the safety switching device shown in FIG. 1;

FIG. 7 is a right side view of the safety switching device shown in FIG. 1;

FIG. 8 is a perspective view of a second embodiment of the safety switching device embodying our new design;

FIG. 9 is a front view of safety switching device shown in FIG. 8;

FIG. 10 is a rear view of the safety switching device shown in FIG. 8;

FIG. 11 is a top view of the safety switching device shown in FIG. 8;

FIG. 12 is a bottom view of the safety switching device shown in FIG. 8;

FIG. 13 is a left side view of the safety switching device shown in FIG. 8; and,

FIG. 14 is a right side view of the safety switching device shown in FIG. 8.

The broken lines in the figures are for the purpose of illustrating portions of the safety switching device that form no part of the claimed design.

1 Claim, 10 Drawing Sheets
